UNITED STATES PATENT OFFICE.

ED ELIAS CURTISS, OF SPOKANE, WASHINGTON.

KEYHOLE-GUARD.

1,223,477.

Specification of Letters Patent. Patented Apr. 24, 1917.

Application filed January 25, 1917. Serial No. 144,482.

To all whom it may concern:

Be it known that I, Ed E. CURTISS, a citizen of the United States, residing at Spokane, in the county of Spokane and State of Washington, have invented certain new and useful Improvements in Keyhole-Guards, of which the following is a specification, reference being had to the accompanying drawings.

10 This invention relates to certain improvements in key hole guards and it is an object of the invention to provide a novel and improved device of this general character wherein a key is effectively held against removal from the lock so that the insertion of a second key or other implement for adjusting the lock into an open position is effectively prevented.

15 The invention also has for an object to provide a novel and improved device of this general character which serves to substantially close the key hole in a door or the like to prevent visual access being had through the key hole.

20 The invention consists in the details of construction and in the combination and arrangement of the several parts of my improved key hole guard whereby certain important advantages are attained and the device is rendered simpler, less expensive and otherwise more convenient and advantageous for use, all as will be hereinafter more fully set forth.

25 The novel features of the invention will hereinafter be definitely claimed.

In order that my invention may be the better understood, I will now proceed to describe the same with reference to the accompanying drawings, wherein—

30 Figure 1 is a fragmentary view in elevation of a fragment of a key hole or escutcheon plate showing certain features of my invention with the coacting key indicated in section and in locked position;

35 Fig. 2 is a vertical sectional view taken through the device as shown in Fig. 1 with the key shown in initial position;

40 Fig. 3 is an inside elevational view of certain parts of my improved guard as herein embodied, the lever plate being indicated by dotted lines;

45 Fig. 4 is a view in inside elevation of the guide plate as herein embodied; and

50 Fig. 5 is an elevational view of the lever plate as herein employed.

As disclosed in the accompanying draw-

ings, P denotes a key hole or escutcheon plate of predetermined dimensions and configuration and which is provided with the key hole 1 through which is adapted to be inserted a conventional key for adjusting a lock into either open or closed position.

Secured to the surface of the door or the like immediately adjacent the plate P is the guide plate 2 disposed transversely of the plate P and provided with the key hole 3 in register with the key hole 1 hereinbefore referred to. The upper and lower marginal portions of the plate 2 are provided with the flanges 4 extending in a direction toward the plate P and between which is adapted to slide the locking plate 5.

The locking plate 5 is also provided with the key hole 6 adapted to register with the holes 1 and 3 so that a key may be inserted therethrough to have proper coaction with a lock mechanism, said key being preferably of a type including a blade B and a shank S angular in cross section as illustrated in Fig. 1 of the accompanying drawings. The enlarged or upper portion of the key hole 6 has in communication therewith the perpendicularly related slot 7 preferably extending to the left, although I do not wish to be understood as limiting myself in this particular respect.

After the blade B of the key has been inserted through the registering openings to adjust the lock mechanism into operative position the blade B will be substantially horizontal and when the locking plate 5 is moved toward the right the shank S of the key will be received within the slot 7, whereby it will be perceived that the key is effectively held against removal. It will also be at once self-evident that when the plate 5 is moved toward the right the opening 6 therein will be adjusted out of register with the openings 1 and 3, whereby said openings are effectively closed against visual access.

K denotes a knob provided at one end with a shank 8, the inner end portion of said shank being circular in cross section so that the knob may be rotatably engaged with the plate P. The shank 8 extends through the plate P and has its free end portion angular in cross section, as indicated at 9, and which is adapted to extend within a correspondingly formed opening 10 produced in the lever plate 11 adjacent an end of said plate.

The plate 11 is preferably vertically disposed and its lower end portion overlies the

upper marginal portion of the plate 5 and said plate 5 is provided with an enlarged opening or slot 12 adapted to loosely receive the pin 14 or the like carried by the overlying portion of the lever plate 11 whereby it will be at once self-evident that the desired sliding movement may be imparted to the plate 5 upon requisite rotation of the knob K.

From the foregoing description, it is thought to be obvious that a key hole guard constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. In combination with a plate provided with a key hole, a plate slidably supported rearwardly of the first named plate and provided with a key hole adapted to register with the key hole of the first named plate, said second named plate being also provided with a slot in communication with the key hole opening at an end thereof, said slot being angularly related to the key hole and adapted to receive the shank of a key when

said second named plate is moved in one direction, a lever plate mounted for rocking movement and having an end portion overlying the second named plate, means for rocking the lever plate, and a pin carried by the overlying portion of the lever plate, said second plate being provided with an opening loosely receiving said pin.

2. In combination with a plate provided with a key hole, a guide plate supported adjacent the first named plate and provided with a key hole in register with the key hole of the first named plate, a locking plate slidably engaged with the guide plate, said locking plate being provided with a key hole adapted to register with the key holes in the first two named plates, said locking plate being also provided with a slot in communication with an end portion of the key hole therein, said slot being also angularly related to the key hole and adapted to receive the shank of a key when said second named plate is moved in one direction, a lever plate mounted for rocking movement and having a portion overlying the locking plate, means for rocking the lever plate, and a pin carried by the overlying portion of the lever plate, said locking plate being provided with an opening to loosely receive the pin of the lever plate.

In testimony whereof I hereunto affix my signature in the presence of two witnesses.

ED ELIAS CURTISS.

Witnesses:

HENRY SEDDON DAVIES,
STEPHEN T. BONNER.
